UNITED STATES PATENT OFFICE.

EDGAR A. RUSSELL, OF WALLINGFORD, CONNECTICUT.

DESIGN FOR A SHADE-HOLDER.

SPECIFICATION forming part of Design No. 29,224, dated August 16, 1898.

Application filed July 25, 1898. Serial No. 686,846. Term of patent 7 years.

To all whom it may concern:

Be it known that I, EDGAR A. RUSSELL, of Wallingford, in the county of New Haven and State of Connecticut, have invented and produced a new Design for a Shade-Holder for Incandescent Electric Lamps; and I do hereby declare the following, when taken in connection with the accompanying drawings and the letters of reference marked thereon, to be a full, clear, and exact description of the same, and which said drawings constitute part of this specification, and represent, in—

Figure 1, a plan view of the shade-holder embodying my design; Fig. 2, a view thereof in side elevation.

This invention relates to a design for a shade-holder for incandescent electric lamps; and the design consists in the configuration hereinafter described, and shown in the accompanying illustration.

As herein shown, my newly-produced design consists of an open ring A, the two arms of which correspond to each other in length, and are furnished at their outer ends with corresponding fingers A' A'. This ring is located centrally above an annular rim B, having a depending annular flange B', formed with depending perforated lugs B². The rim B is

connected with the lower edge of the middle portion of the ring by a horizontally-arranged inwardly-extending web C. A finger D, arranged between the fingers A' and A', is located in a plane parallel with the planes thereof and coincident with a plane intersecting the true center of the ring A and the longitudinal center of the web C. The said finger D extends upward from a horizontally-arranged inwardly-projecting arm D', extending inward from the rim B and located nearly opposite the web C. The rim B is virtually encircled by a rib E, the ends of which are turned inward to follow the edges of the web C and so as to form hook-like extensions E' E'. The arm D' is formed with a V-shaped gib E², the ends of which merge into the rib E. 45

I claim—

The design herein shown and described for the shade-holder for incandescent electric lamps.

In testimony whereof I have signed this 50 specification in the presence of two subscribing witnesses.

EDGAR A. RUSSELL.
